UNITED STATES PATENT OFFICE

2,472,005

BOTTLE CARRIER

Jan de Swart, Los Angeles, Calif., assignor, by
mesne assignments, to Shellmar Products Cor-
poration, Chicago, Ill., a corporation of Dela-
ware

Application December 12, 1944, Serial No. 567,863

11 Claims. (Cl. 224—45)

1

My invention relates to bottle carriers, more particularly to carriers adapted to support a group of bottles so that they can be conveniently carried as a unit. Among the objects of my invention are:

First, to provide a bottle carrier which is particularly inexpensive and simple of manufacture, and which employs a minimum amount of material so that the bottle carrier may be disposable or expendable,

Second, to provide a bottle carrier which engages and supports the bottles by their neck portions in such a manner that they are securely restrained against accidental release, but may be readily removed when desired, one at a time, without disturbing the remaining bottles.

Third, to provide a bottle carrier which may be so arranged as to provide support for additional tiers of bottles so that groups of bottles in their bottle carriers may be stacked or otherwise packed.

With the above and other objects in view as may appear hereinafter, reference is directed to the accompanying drawings in which:

Fig. 1 is a partial sectional, partial side elevational view of one form of my bottle carrier;

Fig. 2 is a transverse sectional view thereof taken through 2—2 of Fig. 1 and showing fragmentarily a bottle suspended therein;

Fig. 3 is a transverse sectional view similar to Fig. 2, but showing the carrier in its open position and illustrating by solid lines the position of a bottle when supported in the carrier and by dotted lines the position of a bottle when in position for removal from the carrier;

Fig. 4 is a fragmentary top view of the carrier when in the open position shown in Fig. 3 and indicating by dotted outlines the position of a bottle when supported and when free of the carrier;

Fig. 5 is a transverse sectional view through 5—5 of Fig. 6, showing a modified form of my bottle carrier wherein the upper side thereof is flat so that the other bottles may be set thereon as indicated by dotted lines;

Fig. 6 is a partial plan, partial sectional view of the construction shown in Fig. 5;

Fig. 7 is a partial sectional, partial side elevational view of a further modified form of my bottle carrier, the view being taken through 7—7 of Fig. 8;

Fig. 8 is a partial plan, partial sectional view of this form of bottle carrier taken through 8—8 of Fig. 7;

Fig. 9 is a transverse sectional view thereof taken through 9—9 of Fig. 7, showing by solid

2

lines the position of two bottles when supported by the carrier and indicating by dotted lines the manner in which the bottles are removed therefrom;

Fig. 10 is a partial side elevational, partial sectional view of a further modified form of my bottle carrier;

Fig. 11 is a transverse sectional view thereof through 11—11 of Fig. 10; and

Fig. 12 is a developed view thereof.

10 With reference first to the construction shown in Figs. 1 through 4, the bottle carrier is formed of a single piece of sheet material which may be cardboard, plastic, or other suitable foldable material. The carrier comprises a base plate 1, side walls 2 formed along the two sides of the base plate, and a top deck 3 formed by bringing the extremities of the sheet over the base plate. The extremities of the sheet from which the carrier is formed, are then turned upwardly to form a handle 4 extending along the center of the top deck 3. Registering slots 5 are provided in the handle. One of the slots may be entirely cut out, whereas the other slot need be cut on only three sides to form a flap 6 which is folded through the slots to reinforce the handle and secure together the two parts from which the handle is formed.

15 A series of clearance openings 7 are cut in the base plate 1 and adjacent portions of the side walls 2. In the structure illustrated, three such clearance openings are provided along each side of the base plate. The clearance openings are circular and large enough to admit the head H of a bottle B including the cap C thereon. The side 20 of each clearance opening 7 formed in the base plate 1, is provided with a lateral slot 8 of smaller diameter. The slots 8 are large enough to admit the neck N of the bottle but are too small to pass the head H. The positions of the slots 8 which

25 may be designated neck-supporting slots, are such that when the side walls 2 are in rightangular relation with the base 1, the side walls hold the bottles in the neck-supporting slots 8. In order to release the bottles it is necessary to open the carrier by unfastening the handle 4 and spreading it apart to the position shown in Figs. 3 and 4. The bottles may then be moved from the solid line to the dotted line position shown in Fig. 3 and removed.

30 Reference is now directed to the construction shown in Figs. 5, 6, 7, 8, and 9. The construction here illustrated is likewise formed from a single sheet of material and comprises a bottom plate 11, side walls 12, and deck flaps 13. The carrier

is thus folded into a tube of rectangular cross-section. The top deck flaps 13 overlap each other and are provided with registering hand slots 14. One's fingers may be readily inserted in the slots and straddle the head of the central bottle so that the carrier and bottles may be easily transported.

The bottle carrier may be provided with the openings 7 and neck supporting slots 8 as shown in Figs. 5 and 6, and in this respect is similar to the construction shown in Figs. 1 through 4, in which case the carrier is unfolded in order to release the bottles.

In Figs. 7, 8, and 9, a modified means of supporting the bottles is illustrated. In this construction the base plate 11 is provided with a row of centrally disposed clearance openings 17 which may be rectangular in form. Opposite sides of the clearance openings are provided with neck supporting slots 18 directed toward the side walls 12. The openings 17 and slots 18 are so proportioned that when two bottles are supported by the slots 18 they hang in contact with each other and force their neck portions to the lateral extremities of the slots 18. It is merely necessary to tilt one of the bottles as indicated by dotted lines in Fig. 9, in order to move the head H thereof into the clearance opening 17.

Both of the constructions shown in Figs. 5 and 6 and in Figs. 7, 8, and 9, require a minimum amount of material. Furthermore, the top deck flaps 13 are flat and provide a surface for the support of other bottles, as indicated by dotted lines in Fig. 5. Thus a number of carriers with their bottles inserted therein may be readily stacked in tiers. Furthermore, when the bottles are packed in boxes for shipment, they may first be inserted in their respective carriers, for the carriers do not take up any appreciable space that would otherwise be used to pack the bottles. While two bottles are shown in contact with each other in Fig. 9, it should be pointed out that the neck supporting slots 18 may be sufficiently wide to permit insertion of a spacer between the bottles when a number of units are packed in a shipping case. This is likewise true of the arrangement shown in Figs. 5 and 6.

Reference is now directed to the construction shown in Figs. 10, 11, and 12. The construction here shown is likewise formed from a single sheet of material and comprises a base plate 21, side walls 22, and top deck portions 23. As in the first described structure the extremities of the sheet from which the carrier is formed, are bent upwardly from the top deck to form a handle 24 having mating slots 25 therein. One of the slots may be completely cut out, whereas the other slot may be only partially cut out to form a flap 26 adapted to be folded through the slots to secure the two parts of the handle 24 together. The side walls 22 are provided with a series of clearance slots 27. Neck supporting slots 28 extend from the clearance slots to the bottom edges of the side walls 22 and into the sides of the base plate 21. When the base plate, side walls, and top deck portions are folded, they define a tube of rectangular cross-section. The heads of the bottles are adapted to be inserted laterally into the tube thus formed through the clearance slots 27, and be lowered until engaging the neck supporting slots 28. The juncture of the clearance slots and neck supporting slots form, when the carrier is folded, upstanding shoulders 29 which prevent the bottles from being removed from the carrier unless they are raised from the base plate 21.

In the construction shown in Figs. 10, 11, and

12, the top deck portions 23 are flat as in the case of the constructions shown in Figs. 5 to 8, and serve similarly to provide a surface for the support of other bottles so that the carriers and their bottles may be stacked. The handle 24 forms a spacer between the bottles so stacked, as shown by dotted lines in Fig. 11.

While it is preferred to make the bottle carriers from inexpensive materials such as sheet card-board or plastic materials, particularly in regard to the constructions shown in Figs. 1 through 6 wherein the carrier must be open or spread apart in order to release the bottles, it should be noted that the carriers, particularly the constructions shown in Figs. 7 through 12, inclusive, may be formed of metal and be relatively rigid in which case, of course, the carriers are used repeatedly.

Many other embodiments of the invention may be resorted to without departing from the spirit of the invention.

I claim:

1. A bottle carrier comprising a single piece of sheet material folded to provide a bottom wall, a top wall and side walls joining said top and bottom walls, said bottom wall being substantially horizontal and having means for supporting by their necks a row of bottles, said top wall overlying the tops of said bottles to form a deck for supporting by their base ends a tier of bottles, and said top wall being provided with handle means.

2. A carrier for bottles having reduced neck portions and enlarged head portions, comprising: a bottom, a top, side walls joining said top and bottom; said bottom having rows of apertures adjacent said side walls adapted to receive the neck portions of bottles, and suspend said bottles by their head portions; said carrier having means adjoining said apertures adapted to clear and pass the heads of said bottles; said top overlying said bottles to form a deck for supporting by their base ends a tier of bottles; and a handle for said top whereby said bottles are carried by said bottom with said bottom in a substantially horizontal position.

3. A carrier for bottles having reduced neck portions and enlarged head portions, comprising: a tubular member of rectangular cross-section including a bottom plate, side walls and a top deck; said bottom plate having a plurality of spaced bottle neck receiving and head retaining openings whereby bottles may hang suspended from said member, there being clearance slots in the side walls in communication with said openings to permit removal of said bottles from said member; the top deck of said member adapted to support by their base ends other bottles whereby said carriers and the bottles carried thereby may be stacked in tiers.

4. A construction as set forth in claim 3, wherein: said openings are arranged in rows along the margins of said bottom plate and continue into said side walls and said clearance slots are disposed in said side walls whereby said bottles are removed by laterally outward movement relative to said bottom plate, and elevated to enter said clearance slots.

5. A bottle carrier adapted to support a group of bottles by their neck portions, comprising: a single piece of foldable sheet material including a bottom plate, side walls, top deck and a handle for said top deck; said bottom plate having a plurality of bottle supporting slots which include neck receiving and head supporting portions, and head clearing portions, said head clearing por-

75

tions extending into said side walls and being inaccessible when said sheet material is folded but being accessible when said sheet material is unfolded.

6. A carrier for bottles having reduced neck portions and enlarged head portions comprising a bottom, a top, and side walls joining said top and bottom, said bottom having rows of apertures adjacent said side walls adapted to receive the neck portions of bottles and suspend said bottles by their head portions, said bottom having clearance openings connecting said bottle neck receiving apertures in pairs, said clearance openings being adapted to clear and pass the heads of said bottles, said top overlying said bottles and having a handle forming portion whereby said bottles are carried by said bottom with said bottom in a substantially horizontal position.

7. A bottle carrier comprising a single piece of sheet material folded into substantially rectangular cross-section with juxtaposed portions at its upper side, said juxtaposed portions being provided with cooperating hand holds, and said carrier having bottle neck supporting slots at least in part in its lower side and having bottle head clearance slots in communication with said supporting slots whereby the bottles may be supported by their necks when said lower side of said carrier is in a substantially horizontal position.

8. A bottle carrier comprising a one-piece sheet material frame having a top deck, a bottom deck and upstanding side walls connecting said top and bottom decks, said bottom deck being generally horizontal and provided with rows of slots for receiving the neck portions of bottles and supporting the same therefrom, said slots extending outwardly to merge with clearance apertures which terminate in said upstanding side walls whereby the heads of the bottles may be passed through said clearance apertures to engage the necks of the bottles with said supporting slots.

9. A bottle carrier comprising a top wall, a bottom wall and vertical side walls connecting said top and bottom walls, said top wall including portions provided with handle forming means, said bottom wall being provided with rows of bottle neck supporting slots adjacent each of the side walls, said supporting slots extending a short dis-

tance into said side walls and said side walls having clearance apertures for passing the heads of bottles whereby the bottles may be positioned for supporting engagement in said supporting slots.

- 5 10. A bottle carrier comprising a top wall, a bottom wall and vertical side walls connecting said top and bottom walls, said top wall including portions provided with handle forming means, said bottom wall and said side walls being provided with rows of transverse slots having relatively wide bottle head clearing portions terminating in said side walls and relatively narrow bottle neck engaging and supporting portions terminating in said bottom wall whereby bottle heads may be passed through said relatively wide portions of said slots to engage the necks of the bottles in supporting relation in said relatively narrow portions of said slots.
- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
